PRINTING MACHINE

Walter T. Gollwitzer, Chicago, Ill., assignor to
Addressograph Company, Wilmington, Del., a
corporation of Delaware

Original application July 23, 1930, Serial No.
469,953. Divided and this application July
25, 1931, Serial No. 553,122

11 Claims. (Cl. 101—58)

This is a division of my application, Serial No. 469,953, filed July 23, 1930.

This invention relates to matrices of the kind used to determine the operation of selector mechanisms of the type employed in printing machines and the like. In printing machines through which a plurality of printing devices are sequentially passed, a selector mechanism is often used to so control the operation of the machine 10 that certain of the printing devices pass through the machine without impressions being made therefrom; or so that a varied number of impressions will be made from the respective printing devices; or so that the sheet or sheets receiving the impressions may be shifted into predetermined positions as different printing devices move into printing position; or for other variable functioning of the machine. Such operation of the selector mechanism is determined by the cooperation of the detecting portions thereof with identifying means on the printing devices. The identifying means may be tabs, lacuna or the like and may be permanently or detachably associated with the printing devices. By arranging 20 the detecting portions of the selector mechanism to cooperate with only predetermined of the identifying means, the selector mechanism will bring about the desired operation of the machine. But it is important that the detecting portions 25 be accurately arranged or set up for otherwise operation of the machine in other than the desired manner will result.

The salient objects of my invention are to provide a novel device in the form of a matrix of simple and economical construction which may be used in a selector mechanism to accurately determine the set-up of the detecting portions; to provide a matrix that may be made from a standard form which may be easily converted into an individual form differing from other matrices made from similar standard forms; and to so construct the standard forms that a large number of different matrices may be made therefrom.

A further object is to provide a matrix which not only cooperates with the detecting portions of the selector mechanism to determine the set-up thereof but which also embodies a variable arrangement adapted to cooperate with an adjustable device in the selector mechanism whereby variation of the variable arrangement imparts further individual characteristics to the matrix to afford additional alteration of the functioning of the selector mechanism in controlling the operation of the machine.

Other and further objects are set forth in the

following description in which reference is made to the accompanying drawing illustrating a selected embodiment of the invention and wherein

Fig. 1 is an elevation of the matrix;

Fig. 2 is a sectional view taken substantially on the line 2—2 on Fig. 1;

Fig. 3 is an end-elevation of a modified form;

Fig. 4 is a sectional view, similar to Fig. 2, drawn to an enlarged scale, and illustrating the modification shown in Fig. 3;

Fig. 5 is a view similar to Fig. 3 of another modified form; and

Fig. 6 is a fragmentary view similar to Fig. 4 and illustrating the modification shown in Fig. 5.

The matrix illustrated in the accompanying drawing comprises a substantially rectangular body 5 preferably formed from a flat sheet of suitable metal. On one of the longer edges of the rectangular body is a projection 6 affording a handle or grip to facilitate installation of the matrix in, and removal therefrom, the selector mechanism, an opening 7 being provided to further facilitate these operations. This projection also prevents inverted installation of the matrix. Matrices of this character are made from standard forms which are provided, in the present instance, with two rows of openings 8 extending parallel to the longer edges of the rectangular body 5, and each of the openings in one row is aligned with a corresponding opening in the other row. To provide a matrix which will bring about a desired operation of the machine, plugs 9 are inserted in certain of the openings 8 whereby a matrix having individual characteristics will result which will differ from other matrices formed from the standard form not having plugs 9 correspondingly arranged in the openings 8 therein. In the embodiment of the invention illustrated in Figs. 1 and 2, the plugs 9 are of a thickness equal to the thickness of the body 5 and the faces of the plugs are aligned with the faces of the body. By plugging but one of the openings or by plugging two or more openings in combination a large variety of matrices may be made from the standard form. Production of an individual matrix from a standard form may be facilitated by closing all of the openings in such standard form with removable plugs and then by merely forcing out the plugs from determined openings an individual matrix may be produced. In order to increase the possible number of individual matrices that may be made from the standard form, I utilize plugs of a thickness greater than the thickness of the body 5, this being illustrated in Figs. 3 to 6, inclusive.

By referring to Fig. 4 it may be

5

seen that a plug 9' has been inserted into one of the openings 8 and that this plug includes a portion 11 which projects beyond the face of the matrix in a definite amount when the opposite end of the plug is arranged to be flush, or substantially so, with the back of the matrix. By utilizing plugs, such as 9', it is manifest that the number of individual matrices, which may be made from the standard form, is greatly increased and to further increase the possible number of individual matrices plugs such as 9" (Fig. 4) may be used which include portions 12 that project beyond the face of the matrix in an amount appreciably greater than the portion 11. In the embodiment of the invention illustrated in Fig. 4, the portion 12 projects beyond the face of the matrix in an amount twice as great as the projection of the portion 11 and preferably this or some other definite relation is maintained between the amount of projection of the portions 11 and 12 beyond the face of the matrix, the relation in the present instance being illustrated by the broken line on Figs. 3 and 5. Hence, it is manifest that by using plugs 9, 9' and 9" singly or in combinations a very large variety of matrices having individual characteristics may be made from the standard forms. If desired, the projecting plugs may be used to bring about special operation of the selector mechanism, as, for example, the operation of a signal or the like.

The portions of the matrix thus far described are those which are used to determine the set-up of the detecting portions of the selector mechanism but to further increase the number of individual matrices which may be made from the standard form I provide a variable arrangement in a form that is adapted to cooperate with adjustable means in the selector mechanism. This adjustable means may be in the nature of a reversing mechanism whereby when it is arranged in one position it will cause the selector mechanism to bring about a certain operation of the machine, as for example, to cause the machine to make impressions from all printing devices having a certain identifying means thereon but by arranging the reversing mechanism in another position the selector mechanism will bring about such functioning of the machine that all the printing devices having a certain identifying means thereon will not have impressions made therefrom or, as it is termed, these printing devices will be skipped. I provide an arrangement whereby an individual matrix may only be inserted into the machine when the adjustable means is arranged in a certain position and to this end the adjustable means is preferably provided with a pin or other suitable protuberance which will register with a slot 10 formed in the edge of the body 5 opposite that having the projection 6. By locating this slot 10 either in the full or dotted-line position shown in Fig. 1, the matrix can be arranged so that it will only cooperate with the adjustable means in the selector mechanism when it is disposed in a predetermined position, for otherwise the pin on the selector mechanism will not enter the slot in the matrix and hence the matrix cannot be inserted into proper operating position.

A matrix so made from a standard form will have individual characteristics as has been previously described and these individual characteristics may be used to bring about a selective classification whereby when the detecting portions of the selector mechanism cooperate with the identifying means on the printing devices, only those

printing devices having identifying means corresponding to the selective classification represented by the matrix will cause the selector mechanism to function in a predetermined manner to thereby bring about the desired operation of the machine.

While I have illustrated and described a selected embodiment of my invention, it is to be understood that this is capable of variation and modification and I therefore do not wish to be limited to the precise details set forth but desire to avail myself of such changes and alterations as fall within the purview of the following claims.

I claim:

1. A matrix for controlling the selection of printing devices sequentially moving through a printing machine and including parts adapted to be removably engaged in a matrix retaining means in the printing machine whereby one matrix may be removed from the retaining means and another substituted therefor, said matrix comprising a body having a plurality of openings therein, and plugs secured in one or more of said openings to impart individual characteristics to the matrix.

2. A matrix for controlling the selection of printing devices sequentially moving through a printing machine and including parts adapted to be removably engaged in a matrix retaining means in the printing machine whereby one matrix may be removed from the retaining means and another substituted therefor, said matrix comprising a body having a plurality of openings therein, and plugs secured in one or more of said openings and extended above one face of the body of the matrix to impart individual characteristics to the matrix.

3. In a matrix comprising a flat substantially rectangular plate having rows of openings therein extending substantially parallel with the longer edges of the plate with each opening in one row aligned with a corresponding opening in the adjacent row to thereby provide pairs of openings, each pair of openings affording a control position, and plugs secured in selected openings of said pairs of openings to impart individual characteristics to the matrix at selected of said control positions.

4. In a matrix comprising a flat substantially rectangular plate having rows of openings therein extending substantially parallel with the longer edges of the plate with each opening in one row aligned with a corresponding opening in the adjacent row to thereby provide pairs of openings to afford a plurality of control positions, and plugs secured in selected openings of said pairs of openings to impart individual characteristics to the matrix at selected of said control positions, said plugs including portions projecting above a face of the matrix in predetermined amounts to thereby impart further individual characteristics to said matrix.

5. In a standard form for a matrix comprising a body having two rows of openings therein with each opening in one row aligned with a corresponding opening in the adjacent row to thereby provide pairs of openings to afford a plurality of control positions, and removable plugs frictionally secured in said openings and adapted to be forced therefrom to impart individual characteristics to said standard form and provide a matrix.

6. In a standard form for a matrix comprising a body having rows of openings therein and having each opening in one row aligned with a corresponding opening in the adjacent row, means

cooperating with said openings to impart individual characteristics to said standard form to provide a matrix, and means imparting additional individual characteristics to said matrix.

- 5 7. In a standard form for a matrix comprising a substantially rectangular body having rows of openings therein extending parallel with the longer edges of said body and having each opening in one row aligned with a corresponding opening in the adjacent row, and said body having a notch in one of the longer edges thereof adapted to be positioned at a predetermined place along said edge.
- 10 8. In a matrix comprising a body having rows of openings therein with each opening in one row aligned with a corresponding opening in the adjacent row, plugs secured in selected of said openings to impart individual characteristics to said matrix, and said body having a slot in one of the edges thereof adapted to be arranged in alternate positions to impart additional individual characteristics to said matrix.
- 15 9. In a matrix comprising a body having rows of openings therein with each opening in one row aligned with a corresponding opening in the adjacent row, plugs secured in selected of said openings to impart individual characteristics to said matrix, and said body having a slot in one of the edges thereof adapted to be arranged in alternate positions to impart additional individual characteristics to said matrix.
- 20 10. In a standard form for a matrix comprising a body having rows of openings therein with each opening in one row aligned with a corresponding opening in the adjacent row, and removable plugs of varied thickness secured in said openings with corresponding ends thereof substantially flush with one face of the matrix whereby the opposite ends of said plugs are flush with or project beyond the other face of the matrix in an amount dependent upon the thickness of the plugs.
- 25 11. In a matrix comprising a body having rows of openings therein with each opening in one row aligned with a corresponding opening in the adjacent row, plugs secured in selected of said openings to impart individual characteristics to the matrix, said plugs including portions projecting above the face of the matrix, certain of said plugs projecting above the face of the matrix in an amount substantially twice the extent of other of said plugs.

ings to impart individual characteristics to said matrix, and means imparting additional individual characteristics to said matrix.

10. In a standard form for a matrix comprising a body having rows of openings therein with each opening in one row aligned with a corresponding opening in the adjacent row, and removable plugs of varied thickness secured in said openings with corresponding ends thereof substantially flush with one face of the matrix whereby the opposite ends of said plugs are flush with or project beyond the other face of the matrix in an amount dependent upon the thickness of the plugs.

11. In a matrix comprising a body having rows of openings therein with each opening in one row aligned with a corresponding opening in the adjacent row, plugs secured in selected of said openings to impart individual characteristics to the matrix, said plugs including portions projecting above the face of the matrix, certain of said plugs projecting above the face of the matrix in an amount substantially twice the extent of other of said plugs.
